ICED CAKE

Edward Brenner and Hymie Brenner, Arlington, Va.

Application November 19, 1953, Serial No. 27,665

Term of patent 14 years

(Cl. D82—2)

To all whom it may concern:

Be it known that we, Edward Brenner and Hymie Brenner, both citizens of the United States, and residing at Arlington, in the county of Arlington, State of Virginia, have invented a new, original, and ornamental Design for an Iced Cake, of which the following is a specification:

Reference is had to the accompanying drawing forming a part of the instant application in which is shown a front perspective view of the iced cake according to our new design.

We claim:

The ornamental design for an iced cake, as shown.
